ADJUSTABLE NOZZLE

Leo W. Mitchell, San Francisco, Calif.

Application May 11, 1932, Serial No. 610,643

8 Claims. (Cl. 299—115)

My invention relates to improvements in adjustable nozzles, and it consists of the combinations, constructions and arrangements hereinafter described and claimed.

An object of my invention is to provide an improvement over the adjustable nozzle shown in my Patent No. 1,789,491, issued January 20th, 1931. In the patent, I show a nozzle especially designed for fuel oil and having an atomizing cup which is rotated for causing the oil to rotate in one direction. The patent also shows an air conduit having an annular opening disposed concentric with the atomizing cup and vanes placed in the air conduit for causing the air issuing from the annular opening to flow in a direction that will cross the flow of oil as it leaves the atomizing cup. This crossing of the air stream with the oil stream results in a perfect atomization and a proper burning of the mixture.

In the present invention, I show novel means for directing the air stream at the desired angle. I further show means for preventing dripping of the oil from the atomizer cup after the device is turned off.

The device is further designed to make use of gas in place of oil, if that is desired.

Other objects and advantages will appear in the following specification, and the novel features of the device will be particularly pointed out in the appended claims.

My invention is illustrated in the accompanying drawing forming a part of this application, in which:

Figure 1 is a longitudinal section through the entire device, portions being shown in elevation;

Figure 2 is a rear elevation of the device;

Figure 3 is an enlarged sectional view through a part of the device;

Figure 4 is a section along the line 4—4 of Figure 3; and

Figure 5 is a section along the line 5—5 of Figure 3.

In carrying out my invention, I make use of a furnace wall 1, and to this wall, I secure a furnace plate 2. A nozzle protector, indicated generally at 3, is carried by the furnace plate. The parts thus far described are secured to the furnace front 1.

In Figures 1 and 2, I show a blower casing 4, which is hinged at 5 to the furnace plate 2, and this permits the casing to be swung away from the nozzle protector 3 when adjusting the parts in the manner hereinafter described. A nozzle 6 is adjustably secured to the blower casing 4

by screws 7, which are received in slots 8, (see Figure 4), and are secured to the casing 4. The casing 4 may be swung away from the protector 3, and then the screws 7 may be loosened so as to rotate the nozzle 6 into the desired position, whereupon the screws 7 may be tightened.

A perforated flange 9 is carried by the casing 4, and a perforated split ring 10 encircles the flange 9 and has ears 11 connected to each other by a bolt 12. The bolt 12 may be loosened and the ring 10 rotated with respect to the flange 9 so as to vary the size of the air openings, and in this way, the auxiliary air intake is controlled, this air flowing through an annular passage 13 formed by the nozzle protector 3 and the nozzle 6.

In Figure 3, I show an atomizing cup 14 carried by a tubular member 15. Figure 1 shows the member 15 as passing through bearings 16 and as having a pulley 17 secured to the end of the tube projecting beyond the bearings. The pulley 17 has a belt 18 connecting it to a motor 19. The bearings 16 are mounted in a casing 20, which holds oil. The casing 20 is integral with a main air inlet 21 controlled by a damper 22, and the casing 20 also forms a part of a gas inlet 23 that has a valve 24 controlling the flow of gas.

A fan 25 is mounted on the tubular member 15 and is disposed in the casing 4. A disc 26 is carried by ribs 27 which, in turn, are integral with the casing 4. A sleeve 28 encircles the atomizing cup 14 and is carried by the ribs 27. It will be seen from this construction that when the motor 19 is actuated, the tubular member 15 will be rotated and will rotate the fan 25, causing air to be sucked through the air inlet 21 and forced through the space between the nozzle 6 and the sleeve 28. The atomizing cup 14 is also rotated.

One of the principal features of the invention is to direct the stream of air passing through the space 29 defined by the nozzle 6 and the sleeve 28, so that this stream of air will cut across the stream of oil issuing from the cup 14. In Figure 3, I show a disc 30 secured to the nozzle 6 and having a plurality of openings 31. Next to the fixed disc 30, I dispose a plurality of floating discs 32, all having openings 33 registering with the openings 31. A flexible wire 34 is secured to the disc 30 and is passed through registering openings 35 in the discs 32. The free end of the wire is passed through an opening 36 in the sleeve 28, (see Figures 3 and 5), and the sleeve is provided with a recess 37 for receiving the free end of the wire.

When the nozzle 6 is rotated with respect to

the sleeve 28, it will carry the disc 30 therewith. The moving of the disc 30 with respect to the sleeve 28 will cause the wire 34 to flex and the free end to swing in the recess 37. This 5 swinging of the wire 34 into an angular position will cause the discs 32 to swing in the same angular positions and to incline the registering openings 31 and 33 so that air passing through these openings will be directed at the desired 10 angle.

An oil pipe 38 is disposed inside of the tubular member 15, (see Figures 1 and 3), and this pipe carries a mouthpiece 39 that has an upwardly-turned end. An oil drip ring 40 is mounted on 15 the mouthpiece 39. The pipe 38 does not rotate with the tubular member 15, but passes through the member and into a valve 41. An oil inlet pipe 42 communicates with the fuel pipe 38 and the flow of oil is controlled by the valve 41.

20 From the foregoing description of the various parts of the device, the operation thereof may be readily understood.

When using oil, the valve 24 is closed and the valve 41 is opened to permit the desired quantity 25 of oil to flow through the tube 38. The motor 19 is connected with a source of electricity, and this will cause the cup 14 to rotate and will also force air through the passage 29. The amount of air is controlled by the damper 22. The air issuing 30 from the passage 29 is directed by the discs 30 and 32 to cut across the stream of oil issuing from the cup 14. The angle of the flow of air can be regulated in the manner already set forth. The auxiliary air flow through the passage 13 is controlled by the ring 10.

When the device is stopped, oil will not drip from the cup 14 because the mouth 39 is turned up at its end and this prevents the oil in the pipe 38 from draining.

40 When gas is used in place of oil, the valve 24 is opened and the damper 22 is also opened so that the proper proportion of gas and air is delivered to the fan 25. In this case, the cup 14 is not used and the gas and air will issue from the passage 45 29 and will burn upon entering the furnace.

While I have shown only the preferred form of my invention, it should be understood that various changes or modifications may be made within the scope of the appended claims without departing 50 from the spirit of the invention.

I claim:

1. The combination with an air delivery nozzle, of an oil-whirling member mounted in the nozzle and spaced therefrom to form an annular air 55 discharge opening, means for delivering oil to said member for causing a film of oil to be ejected therefrom and adjustable means disposed in said air-delivery nozzle for imparting a swirling movement to air flowing therethrough, said nozzle being 60 fashioned for directing the air into intimate contact with the oil issuing from said oil-whirling member, said means comprising a plurality of discs having registering openings therein for the passage of air therethrough, and means for swinging 65 the discs into different angular positions for causing the aligned openings to direct the air in the desired direction.

75

2. In combination, a nozzle having a fluid passageway, a plurality of coaxially mounted, revolvable discs covering the passageway and having registering eccentric perforations and a connection between the discs whereby rotary movement of one disc is transmitted to the other discs for relative rotation through uniformly decreasing angles.

3. In combination, a nozzle having a fluid passageway, a plurality of coaxially mounted, revolvable discs covering the passageway and having registering eccentric perforations, and a flexible wire extending through the discs in spaced relation to the axis thereof and having one end pivotally secured to a stationary element with slight freedom of sliding motion whereby rotary movement of one disc is partly transmitted to the other discs.

4. In combination, a nozzle having a fluid passageway, a plurality of coaxially mounted revolvable discs covering the passageway and having registering eccentric perforations, a flexible wire extending through the discs in spaced relation to the axis thereof and a stationary object having a recess into which one end of the wire 100 extends, the recess having a restricted entrance for the wire so as to hold the latter against rotary movement at the entrance.

5. In an oil burner, an air delivery nozzle, a revolvable oil whirling member mounted in said nozzle and being spaced therefrom to form an annular passageway, through which air under pressure may be forced, means at the discharge end of the passageway for changing the direction of flow of the air and a non-rotating tube encircling 110 the oil whirling member from the receiving end of the passageway to the direction changing means for keeping the air out of contact with the oil whirling member.

6. In an oil burner, an air delivery nozzle, an oil whirling member mounted in said nozzle and being spaced therefrom to form an annular discharge opening, a plurality of coaxially mounted revolvable discs covering the opening and having registering eccentric perforations and a connection between the discs whereby rotary movement of one disc is transmitted to the other discs for relative rotation through uniformly decreasing angles.

7. In combination, a nozzle having a fluid passageway, a plurality of coaxially mounted revolvable discs covering the passageway and having registering eccentric perforations and a flexible wire extending through the discs in spaced relation to the axis thereof whereby rotary movement of one disc is partly transmitted to the other discs.

8. In combination, a nozzle having a fluid passageway, a plurality of coaxially mounted revolvable discs covering the passageway and having registering eccentric perforations and a flexible wire extending through the discs in spaced relation to the axis thereof whereby rotary movement of one disc is partly transmitted to the other discs, the wire having means associated therewith for limiting its turning movement.

LEO W. MITCHELL.
